UNITED STATES PATENT OFFICE

SELDEN J. GOODWIN, OF SAN FRANCISCO, CALIFORNIA

LOCK DEVICE

Application filed September 17, 1928. Serial No. 306,363.

This invention relates to door locks of the spring latch bolt type and has for its objects the provision of guard means whereby the bolt cannot be opened by an unauthorized person through the use of a thin tool or sheet of material to force back the bolt.

Briefly described my invention comprises applying to the bolt socket of a common striker plate an automatically projecting 10 guard of sheet metal so arranged that the bolt is inaccessible from the front of the door as well as from above and below the bolt.

In the drawings accompanying this application Fig. 1 is an elevation of a common striker plate as used on the jamb of a door to receive the latch bolt.

Fig. 2 is a plan view of my guard which is adapted to fit within the socket of the 20 plate of Fig. 1.

Fig. 3 is an end view of the device of Fig. 2.

Fig. 4 is a bottom view of the device of Fig. 2.

Fig. 5 is a perspective view of the inner or adjustable member of the device shown in Figs. 2, 3 and 4.

Fig. 6 is an elevation of the plate of Fig. 1 fitted to a door jamb and with my device 30 in position within the socket in the jamb and plate.

Fig. 7 is a cross section of a bolted door and jamb taken at a point just above the latch bolt of the door lock, with my invention in place and showing the relation of my guard to the door and jamb.

In the common method of installing spring locks in doors, a bolt or striker plate 1 is countersunk into the jamb 2 of a door and the bolt 40 of the lock merely snaps into place in the socket 3 of the plate.

The door 4 (Fig. 7) is supposed to close against a stop piece usually a separate strip 5 nailed to the jamb 2, but in practice there is 45 nearly always an appreciable crack or clearance as at 6, and also at 7 between the side of the door and the jamb, and it is by reason of this that an unscrupulous person can easily open a spring bolted door of this type, as the bolt 8 of the lock 9 has a beveled face at 8'

and if a sheet of celluloid or the like is pushed into the clearance 6 it will follow over into the clearance 7, reach the beveled face of the bolt and force same back into the lock so that the door may be opened. Or instead of the 55 celluloid a thin blade may be forced between the stop 5 and jamb 2 along the joint 10 until it reaches and forces down the bolt.

Prior attempts made to overcome this weakness in spring locks became concentrated 60 on blocking the passage of an instrument through the joint 10 but have not considered the passage most always present at 6, nor have prior devices guarded the latch from accessibility at a slant from above or below. 65

My invention comprises a sheet metal guard consisting of an inner member 11 adapted to be positioned within and forming an outwardly projecting wall at top, bottom and one vertical edge of the socket 3 of the common 70 striker plate 1 and preferably adjustable in or out of the jamb so that its vertical wall may be made to just touch the face of the lock 9 when the door is closed as indicated at 11' in Fig. 7. 75

The adjustability of member 11 may be effected in various ways but is here shown accomplished by pivoting the inner member at 12 to small ears 13 extending from a plate or frame 14 which, when in place on the jamb, is 80 let into the wood flush with the underside of the striker plate and extending beyond the hole 15 cut in the wood for the bolt to project into. A lip 16 extending from wall 11 of the inner member is threadedly engaged by 85 a small screw 17 countersunk in outer surface of plate 14 so that upon removing plate 1 this screw can be reached for adjustment of member in or out with respect to jamb or frame 14 to just the required amount, though it is obvious that if desired a small hole may be drilled through plate 1 just over the screw 17 so that it can be reached without removing plate 1. End walls 11" on the inner member 90 also project outwardly to the lock above and below the bolt. 95

With the arrangement described the latch bolt is guarded from accessibility from its beveled side as well as top and bottom by a metal wall projecting at right angles from the 100

striker plate and substantially in contact with the metal mortised face of the lock itself, thus rendering the bolt proof against tampering by insertion of tools through passages 6, 7 or 5 10, or even if stop piece 5 was forcibly ripped off by one seeking to open the bolt.

From the above disclosure it will be manifest that walls like 11 and 11" integrally formed with striker plate 1 and projecting from the edge of its bolt opening or socket 10 3 will also form a guard as desired though they would not be adjustable to care for shrinkage of doors and jambs as does the complete arrangement shown in the drawings, and therefore any such modifications as 15 come within the spirit of the invention are intended to be embraced in the appended claims.

I claim:

20 1. In combination with a door lock having its outer face in one plane, a spring bevel-sided bolt adapted to engage the edge of an opening in a striker plate, a rigid wall projecting outwardly from said striker plate 25 guarding the bolt when engaged with the plate of a height to take up the normal clearance between lock and plate when the door is hung and substantially touching the face of the lock exposed at the edge of the door, 30 said wall extending along one vertical edge of said opening adjacent the beveled side of the bolt.

2. In combination with a door lock having its outer face in one plane, a spring bevel-sided bolt adapted to engage the edge of an opening in a striker plate, a rigid wall projecting outwardly from said striker plate guarding the bolt when engaged with the plate of a height to take up the normal clearance 35 between lock and plate when the door is hung and substantially touching the face of the lock exposed at the edge of the door, said wall extending along one vertical edge of said opening past the beveled side of the bolt and for a distance along the upper and lower edges of said opening.

3. In combination with a door lock having a spring bevel-sided bolt adapted to engage the edge of an opening in a striker plate, a 50 rigid wall projecting outwardly from said striker plate guarding the bolt when engaged with the plate, and means whereby said wall is adjustable in its projection from said plate adapting the wall to be brought into contact 55 with the face of the lock exposed at the edge of the door when the bolt and plate are engaged.

4. A striker plate having an opening to receive the latch bolt of a lock, a device under 60 said plate provided with a wall projecting outwardly through said opening extending along one side and both ends thereof.

5. A striker plate having an opening to receive the latch bolt of a lock, a frame positioned under said plate, a bolt guard device 65

provided with a wall projecting through said opening, and means whereby said device may be adjusted relative to said frame and plate to vary the projection of said wall from the face of said plate.

6. In a structure as specified in claim 5, said wall extending along one edge of said opening and for a distance along its two ends.

7. A striker plate having an opening to receive the latch bolt of a lock, a frame positioned under said plate, a bolt guard device provided with a wall projecting through said opening, said device being pivotally mounted on said frame, and a screw connecting the frame and device arranged and adapted for adjusting the frame and device from the pivotal mounting.
